Patented Nov. 25, 1975

237,808

BALL GAME TARGET

Ernest W. Ekstrand, Long Beach, Calif.
(12281 Ellen St., Garden Grove, Calif. 92640)

Filed May 10, 1974, Ser. No. 468,890

Term of patent 7 years

Int. Cl. D21—01

U.S. Cl. D34—5 VV

FIG. 1

FIG. 2

FIG. 3

FIG. 4

FIG. 1 is a front elevational view, in perspective, of a ball game target, showing my new design;

FIG. 2 is a rear elevational view;

FIG. 3 is a side elevational view, the view from the opposite side being identical but reversed; and

FIG. 4 is a top plan view.

I claim:

The ornamental design for a ball game target, substantially as shown and described.
